Patented Nov. 23, 1920.

Inventor
John Erickson,

By Dodge and Sons,

UNITED STATES PATENT OFFICE.

JOHN ERICKSON, OF MADISON, WISCONSIN, ASSIGNOR TO MADISON KIPP CORPORATION, OF MADISON, WISCONSIN, A CORPORATION OF WISCONSIN.

LUBRICATOR.

1,359,584.

Specification of Letters Patent. Patented Nov. 23, 1920.

Application filed July 8, 1920. Serial No. 394,686.

To all whom it may concern:

Be it known that I, JOHN ERICKSON, a citizen of the United States, residing at Madison, in the county of Dane and State 5 of Wisconsin, have invented certain new and useful Improvements in Lubricators, of which the following is a specification.

This invention pertains to lubricators and more particularly to the force-feed type 10 wherein a piston is employed to draw the charge from a reservoir (or the like) into a cylinder, and to eject the same therefrom.

The main object of the present invention is to provide means whereby seepage of the 15 lubricant past and in rear of the piston is prevented as the piston is moved or forced forwardly in its impelling stroke, thus precluding or doing away with the forcing of the lubricant outwardly about or around the 20 piston-rod or stem and onto the hand of the operator as the same is moved outwardly in the act of retracting the piston to draw in another charge. In lubricators of the type herein set forth this outward ejection of the 25 lubricant around the stem has been a more or less serious objection, and the present invention cures the same in a very simple manner.

A structure wherein my invention is embodied is illustrated in the annexed drawings, wherein:

Figure 1 is a longitudinal sectional view of a lubricator with the piston in its retracted position;

Fig. 2 a similar view with the piston moved forwardly or at the end of its ejection stroke; and

Fig. 3 a transverse vertical sectional view on the line $a-a$ of Fig. 2.

In the drawings 1 denotes a cylinder 10 mounted by a reservoir 2 which is in communication with the cylinder through a port 3. The outer end of the piston is in direct communication with a discharge port 4 which opens into a discharge chamber 5 formed within the exteriorly threaded nipple 6. Port 4 is normally closed by a non-return check valve 7 held to its seat by a spring 8 the outer end of which takes against a perforate washer 9. Such valve may, however, be omitted as its presence is not essential to the present invention.

The piston is denoted by 10, and its operating stem or rod 11 extends outwardly 5 therefrom through a bushing 12, the stem preferably having a handle 13 secured there-

to. A spring, as 14, is shown as encircling the stem, bearing at one end on the piston and at its opposite end against the bushing 12, and serving to force the piston to the right to effect the ejecting stroke. Such spring is not, however, essential as the piston may be actuated manually without the aid of the spring.

The inner wall of the cylinder 1 is provided with an interior groove or channel 15 which extends around said wall or face, the groove opening or terminating in the intake port 3. This groove or channel, which may be readily tooled in the face of the cylinder, 65 is preferably located so that it opens into the rear portion of the intake port 3 and provides means whereby seepage or forcing of the lubricant to the rear of the piston or plunger 10 is precluded or done away with. 75

In action and with the parts in the position shown in Fig. 1, the piston or plunger is shown as drawn to the left, in which position the port 3 is uncovered and a charge of lubricant passes into the forward end of the 80 cylinder in advance of the piston. Upon an inward movement of the piston either under the action of spring 14 or by pressure applied to handle 13 (or both), the piston passes under port 3 closing the same, and 85 then forces the entrapped lubricant through port 4, past valve 7, and to the element to be lubricated. During such forcing movement the lubricant, especially if it be a light one, will, to a greater or less extent be forced 90 rearwardly along the peripheral face of the piston, and, with the ordinary construction, such lubricant would pass to the left of the piston and into the space through which the stem or rod 11 extends, from which space it 95 would ultimately be forced onto the hand of the operator. With the provision of the channel 15 such rearward seepage is arrested, any rearwardly traveling lubricant passing into the channel and thence back 100 through the feed port 3 to the reservoir or other source of supply.

By this simple arrangement the use of packing rings on the piston or plunger, or the necessity of any packing gland or stuffing 105 box about the actuating stem or rod, is done away with.

Having thus described my invention what I claim is:

1. In a lubricator the combination of a 110 cylinder having a discharge port and a laterally opening intake port; and a piston

- 2
- mounted for movement in said cylinder, said piston having an amplitude of movement such that it opens the inlet port on the intake stroke of the piston and closes the same during the initial movement of the piston on the ejecting stroke, said cylinder having a channel formed in its face, said channel opening into the inlet port.
2. In a lubricator the combination of a cylinder having a discharge port and an intake port; a piston mounted for reciprocation in said cylinder and acting as a valve for said inlet port; and means for conducting any lubricant which may be forced rearwardly along the piston during the ejecting stroke of the latter to the intake port.

3. In a lubricator the combination of a cylinder having a discharge port at one end thereof; a reservoir in communication with the cylinder through an intake port spaced to the rear of the discharge port, said cylinder having a groove formed in the inner face thereof and opening into the intake port; a piston mounted in the cylinder, said piston acting as a valve to close the intake port upon the ejecting stroke of the piston; and a rod extending from the piston to the outside of the cylinder.

In testimony whereof I have signed my name to this specification.

JOHN ERICKSON.
